UNITED STATES PATENT OFFICE

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY

SKATE

Application filed February 14, 1929. Serial No. 339,860.

One object of the invention is to provide a skate adapted for use in hockey, in speed skating, or under any conditions where lightness and strength are essential.

5 The invention consists in the features and combination and arrangement of parts hereinafter described and particularly pointed out in the claims.

In the accompanying drawings:

10 Figure 1 is a side elevation of a skate embodying the invention.

Fig. 2 is a cross section on line 2—2 of Fig. 1.

15 Fig. 3 is a cross section on line 3—3 of Fig. 1.

Fig. 4 is a perspective view of a preformed reinforcing member to be attached to the upper part of the skate runner and to which the foot supports are to be attached.

20 In these drawings 1 indicates the runner and 2 the sheet metal reinforcing member attached thereto along its upper part. The runner is of plain flat formation, except that it is thinner at its upper portion than at its 25 lower part. It is free from ribs or any formation which would interfere with its formation expeditiously by hot rolling or by cold rolling. By a hot or a cold rolling process this substantially flat blade can be 30 formed to close standards at little expense.

Along the upper portion of the runner there is attached the sheet metal reinforcing member 2 of substantially T shape in cross section, with its sides 2^a slightly spaced apart 35 and embracing the upper portion of the runner 1. The sheet metal member is upset in close formation as to its upper or head portion so that the lateral flanges 3 thereof are made up of closely disposed layers of metal presenting strong, stiff edge portions of the T shaped 40 head. This preformed T shaped member is fixed to the runner by any suitable means, such as riveting the downwardly extending sides or flanges 2^a to the upper thinner portion of the runner. Spot welding may also 45 be used, or soldering.

The foot supports 4 are hollow sheet metal members of substantially inverted frustoconical form. They have flanges at their 50 lower ends which reach under the T shaped

sheet metal rail or member 2. These flanges have substantially horizontal portions 5 which lie directly against the horizontal under faces of the T shaped head of the reinforcing bar and vertical extensions 5^a lie 55 against the vertical flanges of the T shaped member to which they may be secured by soldering, welding, or in other ways, such as riveting. It will be observed that the upper side of the sheet metal T shaped bar 2 is 60 slightly rounded or arched, whereas the under side is substantially horizontal. The lower portions of the foot supports conform to these shapes. As will be noticed, the foot supports have their flanges 5, 5^a bent sharply 65 to conform to the T shaped reinforcing rail or bar, thus contributing to stiffness and strength of the attached parts, and at the fore and rear portions of each foot support there are short portions 5^b of the flanges 70 which are slightly arched and rest upon the upper curved or arched portion of the T shaped rail or bar. The foot supports are provided with suitable flanges 6 for receiving the foot plates 7 when desired. These 75 foot supports or standards are reinforced by ribs or corrugations 8 stamped from the sheet metal, extending vertically and under the lower flanged portions thereof, so that not only are these supports stiffened vertically 80 along their main body portions, but also at their lower flanged portions, where they embrace the T shaped head of the bar or rail 2 attached to the skate runner, so that in addition to the stiffness derived from sharply bending the flanges 5, 5^a, stiffness and 85 strength is derived from the corrugations 8, which are carried down to near the extreme end of the flange 5^a.

The construction above described lends 90 itself to the economical, expeditious and accurate formation of the skate with all the strength, accompanied with lightness, necessary in a racing skate, or in a skate subjected to severe strains, in playing hockey or in 95 stunt skating.

Because the runner is of substantially plain formation, that is constructed in the form of a plain bar, it can be readily rolled, hot or cold, can be ground to refine its dimensions 100

and can be readily straightened if it becomes slightly bent in tempering. Furthermore, the T-shaped member of sheet metal, hardened and tempered, and thereafter applied to the runner, will add its stiffness to the skate and supply any degree of this characteristic which the skate otherwise might lack by reason of softening the upper part of the runner for straightening purposes.

The hollow cup shaped foot supports can be applied to the reinforcing T shaped sheet metal bar either before or after the latter is applied to the skate runner.

The construction described also contributes to the high polish nickel finish demanded in a skate of this type. This high polish finish may be secured because the runner is of the flat blade type, as this lends itself readily to a high polish by machine. The reinforcing bar being made of bright sheet steel, does not require this finishing operation.

The skate may be lightened materially by forming the upper portion of the runner with a series of openings or slots 9. These will be hidden by the flanges of the reinforcing rail or bar, which reach down over them at either side.

I claim:

1. A skate comprising a runner, a substantially T shaped reinforcing bar of sheet metal extending along its upper part having depending flanges embracing and attached to the said upper portion of the runner, and having its head portion provided with closely doubled walls forming lateral edges and substantially horizontal under faces, and foot supports having sheet metal walls individually bent sharply about said edges and against said horizontal under faces, and with flanges sharply bent and lying against and affixed to the depending flanges of the reinforcing bar, substantially as described.

2. A skate according to claim 1 in which the runner is in the form of a plain bar from end to end, the upper part being thinner than the lower part.

3. A skate according to claim 1 in which the runner is perforated along its upper portion, said perforations being covered by the flanges of the T shaped bar, substantially as described.

4. A skate according to claim 1 in which the foot supports are corrugated vertically throughout the sharply bent and flanged lower portions thereof.

5. A skate comprising a runner, a substantially T shaped reinforcing bar of sheet metal previously hardened and tempered and applied along the upper portion of the runner, said reinforcing bar having depending flanges embracing and attached to the said upper portion of the runner, and having its head portion provided with closely doubled walls forming lateral edges and substantially horizontal under faces, and foot supports

having sheet metal walls individually bent sharply about said edges and against said horizontal under faces, and with flanges sharply bent and lying against and affixed to the depending flanges of the reinforcing bar, substantially as described.

In testimony whereof, I affix my signature.

WILLIAM F. REACH.
